[57] CLAIM

The ornamental design for a decorative wheel, as shown and described.

DESCRIPTION

FIG. 1 is a top plan view of a decorative wheel, showing my new design, the bottom view being a mirror image thereof;

FIG. 2 is a top plan view of a second embodiment of that shown in FIG. 1, the bottom view being a mirror image thereof; and

FIG. 3 is a top perspective view of that shown in FIG. 1.
